Term of patent 14 years

(Cl. D11—1)

Fig. 1

Fig. 2

Fig. 3

Fig. 4

Figure 1 is a front elevational view of a meat tenderizer, showing my new design;

Figure 2 is a side view thereof;

Figure 3 is a side view of the side opposite that shown in Figure 2; and

Figure 4 is an end elevational view of the same.

The dominant features of my new design reside in the tapered faces of the head portion and the complementary tapered handle as shown.

I claim:

The ornamental design for a meat tenderizer, as shown and described.
